UNITED STATES PATENT OFFICE.

JOHN A. WERNER, OF DAYTON, OHIO, ASSIGNOR TO THE NATIONAL CASH REGISTER COMPANY, OF DAYTON, OHIO, A CORPORATION OF OHIO, (INCORPORATED IN 1906.)

TOTAL-PRINTING CASH-REGISTER.

1,125,613.

Specification of Letters Patent.

Patented Jan. 19, 1915.

Application filed March 23, 1911. Serial No. 616,294.

To all whom it may concern:

Be it known that I, JOHN A. WERNER, a citizen of the United States, residing at Dayton, in the county of Montgomery and State of Ohio, have invented certain new and useful Improvements in Total-Printing Cash-Registers, of which I declare the following to be a full, clear, and exact description.

10 This invention relates to key operated, total printing cash registers, and among the objects of the invention is to provide an improved total printing device having manually operated interlocking platen and paper feeding devices, whereby a certain order of operation of these devices is essential to obtain impressions.

A further object of the invention is to provide a novel two part key construction 20 whereby when one part is manually operated the other part becomes connected to an operating mechanism and is given its complete movement thereby. Other keys are connected to drive the operating mechanism. 25 Thus a simultaneous depression of keys is not essential and certain keys need only be depressed a slight distance to become effective although the machine is of the key operated type.

30 Another object of the invention is to provide totalizer alining devices operative to aline and lock the totalizer when the totalizer is out of mesh and when the totalizer is in mesh and its actuators are at rest.

35 Another object of the invention is to provide means for automatically restoring the totalizer pinions and carrying devices if by straining the machine the totalizer is overthrown far enough to trip the carrying 40 devices.

Another object of the invention is to provide an autographic attachment to cash registers with a paper feeding mechanism by which the paper may be fed forwardly or 45 rearwardly as desired, for the purpose of receiving new records or bringing old records to view.

Another object of the invention is to provide an improved differential mechanism 50 simple in construction and requiring for operation but a small portion of the stroke of the operating keys.

A further object of the invention is to provide a cash register with indicator screen

mechanism under the control of value and 55 special, transactions or clerks' keys, whereby the operation of any key will cause the screen to move to concealing position, but to remain in concealing position only if no special key is depressed, thus attracting attention to improper operations of the machine.

With these and incidental objects in view, the invention consists in certain novel features of construction and combinations of 65 parts, the essential elements of which are set forth in appended claims, and a preferred form of embodiment of which is hereinafter described with reference to the drawings which accompany and form part of the 70 specification.

Figure 1 is a vertical transverse section showing the main operating and the differential mechanisms. Fig. 2 is a vertical transverse section showing principally certain mechanism operated by the initial keys. Fig. 3 is a detail in plan of the key arresters for the initial keys. Fig. 4 is a right side elevation showing the detail printing mechanism. Fig. 4^a (Sheet 6) is a continuation of 80 Fig. 4 showing an autographic attachment. Fig. 5 is a detail in left side elevation of part of the differential mechanism. Fig. 6 is a detail in left side elevation of the totalizer and its driving mechanism. Fig. 7 is a 85 front elevation of the totalizer. Fig. 8 is a left side elevation of the totalizer with its frame and a carrying frame for alining pawls in section. Fig. 9 is a transverse vertical section of the totalizer showing its carrying mechanism. Fig. 10 is a detail in left side elevation of the mechanism for meshing the totalizer with its actuating devices. Fig. 11 is a detail mainly in plan but partly 90 in section of the totalizer resetting mechanism. Fig. 12 is a detail in front elevation of the totalizer resetting mechanism. Fig. 15 is a sectional detail of the totalizer showing a locking arm and a disk for the carrying mechanism. Fig. 16 is a detail in front elevation of a total printing mechanism and includ-

105

ing the totalizer. Fig. 17 is a detail in front elevation of the platen of the total printing mechanism. Fig. 18 is a top plan of the total printing mechanism. Fig. 19 is a detail in right side elevation of an interlock between the platen operating and the paper feeding devices of the total printing mechanism. Fig. 20 is a detail in right side elevation of the platen operating mechanism.

10 The present invention is shown as applied to a machine of the type described in Letters Patent of the United States No. 497,860 granted to Thomas Carney on May 23, 1893, but it is to be understood that the invention 15 is not limited to use in connection with machines of that type.

Briefly stated the invention relates to a key operated cash register having initial keys, and value keys grouped in denominational banks with connections for setting indicator tablets, for operating a totalizer, and a total printing mechanism. Separately operated total printing mechanism is provided for printing totals from the totalizer.

25 The operating or value keys are all pivoted about midway of their length on a transverse rod extending from side to side of the machine and are properly formed to engage a key coupling device to compel simultaneous and uniform depression of keys. The value keys are provided with operating standards of novel construction, and adapted to cause the desired differential movements of the totalizer operating devices in such a 30 manner as to leave sufficient time for operating a platen or any other desired mechanism, during the time the differentially set mechanisms remain in their adjusted or set positions. The key coupler carries a suitable 35 double rack meshing with a pinion on a cam shaft for the purpose of rotating this shaft. The shaft carries cams for rocking the totalizer into and out of mesh with certain key operated operating devices, for operating totalizer alining devices, and for operating the 40 platen of a detail printing device. It also carries a mutilated gear for operating the totalizer carrying mechanism.

The detail printing mechanism is provided 45 with a paper carrying table normally in position to receive autographic records, and automatically movable at each operation of the machine to receive a printed record at the side of the autographic record. Paper feeding mechanism is provided which is normally driven in one direction by the main operating mechanism of the machine, but which may be manually operated to feed the paper forward or backward to bring any desired record into view.

An autographic attachment is also provided for the purpose of receiving more extended records or memoranda than is possible in the detail printing mechanism. The 60 paper feeding device for the autographic at-

tachment is arranged to be operated through connections to the main operating mechanism of the machine, or may be operated by hand to feed the paper forward or backward.

The total printing mechanism consists of type wheels carried by the totalizer, and a platen, and a paper feeding mechanism, each independently operable, both with reference to each other, and to the main operating mechanism of the machine.

Keyboard.—Referring to the drawings, the value keys 1 and the initial keys 2 are loosely pivoted on a transverse rod 3. The value keys extend rearwardly of the rod 3 beneath a key coupling device 4 and supporting rods 5 for tablet indicators 8. Thus, depression of the value keys serves to lift the desired indicator tablets to view, the tablets being latched in their lifted positions by a spring actuated bar 6 engaging under shoulders 7 on the upright indicator rods 5.

The key coupler 4 is provided with trunnions 9, by which it is pivoted, and with a rearwardly extending shoulder 10 co-acting with notches 11 and curved surfaces 12 of the keys to compel simultaneous and uniform depression of keys. The key coupler is provided with a pin 13 extending through a horizontal slot 14 in an upright double rack 15. The rack has a slot 16 embracing a fixed pin 17 and is thus guided in its vertical movement by the pin but is rocked around the pin so that the sets of teeth 18 and 19 will be alternately meshed with a pinion 20 fast to a shaft 21. This is caused during the reciprocation of rack 15 to rotate shaft 21. Shaft 21 is the main cam shaft of the machine and its function will be pointed out farther on. This arrangement of operating mechanism is similar to that shown in Letters Patent of the United States to Thos. Carney, No. 696,224, Mar. 25, 1902.

The initial keys are novel in construction, being made in two parts, each pivoted on the shaft 3, but only one of which becomes connected to the key coupler by a slight manual depression of the other part. Thus it is unnecessary to depress an initial key simultaneously with the value keys and the forward or operating ends of the initial keys are not required to make as long a stroke as is the case with the value keys. In setting up a number of several denominations it is difficult to depress all of the necessary keys simultaneously as is usually essential in key operated machines. Therefore the present invention provides means whereby, if desired, one bank of keys only need be constructed to have a long operating stroke, as this arrangement of initial keys may equally as well be applied to other banks.

The forwardly extending part 22 of each initial key also extends slightly rearward of rod 3 and at its rear end is provided with

a lug 23 extending below the part 24 of the key. The initial keys are depressible only a slight distance, compared with the stroke of the value keys 1. The depression of an initial key is, however sufficient to lift part 24 of the key into co-acting relation with the key coupler 4 and the parts 24 of the initial keys are provided with latching devices 25, such as described in Letters Patent 10 of the United States granted to W. G. Doty #823,516, June 19, 1906, whereby the key is supported when lifted by the depression of part 22.

Uprights 5 of initial indicator tablets 26 are located above the rear ends of parts 24 of the initial keys, and are thereby lifted into view on the depression of value keys 1, when the key coupler 4 engages the parts 24 and lifts them their full strokes. 15
20 The initial keys control an indicator screen 27 for the value indicators in order to conceal the value indicators if no initial key is depressed on an operation of the machine. The screen 27 is lifted to concealing position on the upward movement of key coupler 4 and for this purpose its supporting and guiding slides 28 are provided with forwardly extending parts 29 resting on the flange 10 of the key coupler. 25
30 When the screen reaches its upper position it is held there by a spring actuated latch 30 pivoted to the frame of the machine by pins 31 and engaging with shoulders 33 on slides 28. The latch 30 has a forwardly extending arm 32 in position to be engaged by lugs 35 on the uprights 5 of the initial indicators. Thus the screen 27 is released whenever an initial indicator is lifted to view. 35
40 If the machine is operated by the depression of value keys alone, the screen 27 will remain in concealing position, thus indicating the fact that the operator failed to depress an initial key. The initial indicators are latched in their upper positions by the 45 latching bar or rod 6.

The rear parts 24 of the initial keys extend forwardly of rod 3 into position to move between key arresters 36. These arresters are pivoted to a slotted plate 37, 50 through which upwardly extending portions 38 of the key parts 24 extend, and are of usual construction, having a limited rocking movement on plate 37 sufficient to permit the passage of only one of the key portions 55 38 at a time. Thus it is impossible to depress more than one initial key at once, and when an initial key is depressed the remaining initial keys are locked against movement.

60 Differential mechanism.—For the purpose of differentially actuating the totalizer and for setting the value type carriers of the detail printing mechanism, each value key 1 has pivoted to its rear end a camming upright 48 (Fig. 1). All of the uprights 48

are identical in form and are guided in their movements by a transverse-rod 49. Each upright 48 is in position to engage one of a group of nine bell crank levers 50 pivoted spirally on a rod 51 and all fast to a totalizer 70 and type wheel actuating segment 52. There is a group of levers 50 for each group of value keys and for each segment 52, thus each segment is adapted to actuate one denominational pinion of the totalizer. The 75 upper ends of the bell crank levers 50 are engaged by the inclined upper surfaces 53 of the uprights 48 and are differentially rocked thereby according to the angular setting of the bell crank levers 50 on shaft 51. 80 Overthrow of levers 50 is prevented by the lower arms 54 of the bell crank levers engaging edges 55 of the uprights 48, when the inclined surfaces 53 complete their action on the upper arms of the bell crank 85 levers 50. Each segment 52 is normally prevented from displacement by a zero stop 56 (Fig. 5) in the form of a bell crank lever pivoted on rod 49 and having one arm 59 normally in the path of one of the bell 90 crank levers 50, thereby locking the segment 52. Each zero stop carries a rod 57 extending over shoulders 58 of its respective group of uprights 48. On the upward movement of any upright or cam member 48 this rod 57 is forced rearwardly, thus carrying the arm 59 of the bell crank lever 56 downwardly out of engagement with the particular bell crank lever 50 with which it normally engages. The bell crank levers 50 and the corresponding segments 52 are then free to be moved to actuate the totalizer and to set the value type carriers. 95

Totalizer.—The totalizer comprises a plurality of type wheels 60 (Fig. 7) loosely journaled on a shaft 61, carried by a supporting frame 62 pivoted on a shaft 63 which in turn is journaled in rigid frames 64 (Fig. 1). The frame 62 extends below the shaft 63 and at its lower end is provided with a pin 65 (Fig. 10) over which is hooked a pitman 66. The pitman 66 is supported by cam shaft 21 and for this purpose is provided with a slot 67 through which the shaft extends. It carries two rollers 68 and 69 positioned to be engaged by cams 70 and 71 fast to shaft 21 and so located on the shaft that before the cam uprights 48 engage the bell crank levers 50, these rollers will force the pitman 66 forwardly, thus rocking the totalizer frame 62 around its pivot 63 and carrying the totalizer pinions 72 into mesh with pinions 73 (Fig. 6) journaled on a rod 74. Each pinion 73 is fast to a pinion 75 meshing with one of the differential segments 52. The totalizer is thus meshed with its actuating pinions 73 before movement of segments 52 occurs, and when these segments are at rest in their moved positions cam 71 engages shoulder 69, re- 110 115 120 125 130

- turning the pitman 66 to normal position and thus rocking the totalizer out of mesh with the pinions 73 so that its setting will not be effected by the return of segment gears 52. The segment gears are returned to normal positions upon release of keys 1 by the key coupler 4 bearing on the feet 235 of links 236 hung from one of each set of bell crank levers 50.
- 10 The totalizer pinions are aligned and locked in their set positions before the totalizer is rocked out of mesh with the pinions 73 and remain locked during the time that the totalizer is out of mesh except at the moment when carrying operations are performed. The aligning devices consist of pawls 76 loosely pivoted on a rod 77 (Figs. 9 and 15). The rod 77 is carried by a frame 78 (Fig. 6) loosely pivoted on shaft 63 and provided 20 with a circular projection 79 extending into a jaw formed in a bell crank lever 80 pivoted on a shaft 81 and extending rearwardly of its pivot into position to be operated by a cam disk 82 fast to shaft 21. The disk 82 25 by engagement with a shoulder 83 of arm 80 serves to hold the frame 78 in a central position during the greater part of the operation of the machine, so that the aligning devices will not engage the totalizer pinions when 30 these pinions are being rotated by pinions 73, but will engage the totalizer pinions when the totalizer frame 62 is rocked forwardly. However, when the totalizer is in mesh and at the moment segments 52 come 35 to rest, a nose 84 on cam disk 82 engages shoulder 83 thus rocking the aligning pawl carrying frame rearwardly and forcing the pawls 76 into engagement with the totalizer pinions. Nose 84 is properly formed again 40 to permit forward rocking of frame 78 as the totalizer frame 62 is rocked forward, but it does not at this time permit pawls 76 to be disengaged from the totalizer pinions, that is, the totalizer pinions and the pawls 76 45 move forward together. By this arrangement the locking and aligning pawls 76 not only serve to prevent rotation of the totalizer pinions when the totalizer is out of mesh with its actuators, but also serve to prevent 50 overthrow of the totalizer pinions when segments 52 come to rest in their moved positions. The totalizer pinions are equipped with trip cams which interlock with the carrying devices, as will hereinafter appear, 55 so that if the carrying devices are partly tripped by an overthrow of the totalizer pinions, the carrying devices will be restored with the pinions by action of the aligning pawls 76.
- 60 The aligning pawls 76 have downward extensions 85 adapted to engage with triangular disks 86 (Fig. 15) loose on a shaft 87 but normally prevented from rotation. The disks 86 thus normally serve to prevent a 65 rocking movement of pawls 76 independ-

ently of the rocking of their carrying frame 78, but are rotated to permit such rocking movement as required during carrying operations.

The carrying devices for the totalizer consist of groups of toothed disks 86, 88, 89 and 90 (Fig. 7). The disks of each group are rigidly secured together but are loosely journaled on shaft 87 and are located intermediate the pinions of the totalizer in positions to carry units of movement from pinions of lower order to pinions of higher order. These disks co-act respectively with the totalizer pinions 72, trip cams 91 fast to the pinions 72, driving cams 92 fast to 70 shaft 63, and the aligning devices 76. Each group of toothed disks 86, 88, 89 and 90 is normally prevented from rotating by the engagement of locking disk 88 with the curved surfaces of cams 91 and 92, and in 75 order to rotate an element of the carrying mechanism a notch 93 in cam 91 or a notch 94 in cam 92 must be in proper position to permit the passage of one of the teeth 95 of disk 88. When a totalizer pinion passes 80 from "nine" to "zero" a bent lug 96 of the cam 91 for that pinion enters one of three notches 97 in the corresponding disk 89, thus rotating the disk 89 and the disks 86, 88, and 90, which are secured thereto, one-sixth of a rotation in the direction indicated by the arrow in Fig. 13. This one-sixth of a rotation serves to bring one of 85 three teeth 98 of disk 90 into such a position (Fig. 9) that, at a second one-sixth rotation of the disk in the same direction, the tooth 98 will engage the pinion 72 of next higher order and rotate it an additional 90 unit in a forward direction. The first one-sixth rotation of the disks also brings one 95 of the teeth 99 of disk 86 into the path of a bent lug 100 extending from the corresponding cam disk 92. The disks 92 are fast to shaft 63, which is given a complete 100 rotation in the direction indicated by the arrow in Fig. 9 after the totalizer is rocked out of mesh with the totalizer actuating pinions, thus effecting the second one-sixth 105 rotation of the tripped carrying devices. Shaft 63 is given this rotation through a 110 geared connection with cam shaft 21, as shown in Fig. 6. Shaft 21 carries a mutilated gear 101 having teeth 102 for engaging, during the latter part of the rotation of shaft 21, with teeth 103 of a mutilated gear 104 journaled on shaft 81. Gear 104 is thus caused to make a one-third rotation 115 at this time and it is fast to a gear 105 meshing with a pinion 106 fast to shaft 63. The one-third rotation given to gear 105 effects a complete rotation of the shaft 63 at 120 which time lugs 100 on the disks 92 engage teeth 99 of such of the disks 86 as have been tripped by the action of lugs 96 on teeth 95 of the companion disks 88. The move 125

130

ment imparted by cam disks 92 to their respective groups of disks on shaft 87 is sufficient to cause teeth 98 of disks 90 to engage and rotate their respective totalizer pinions the desired extra units.

At the time of the engagement of disks 90 with the totalizer pinions, teeth 99 of disks 86 pass away from the lower ends 85 of pawls 76, thus permitting the required 10 rotation of the totalizer pinions, but when the totalizer pinions have completed their single units of movement in carrying, succeeding teeth 99 of disks 86 come in front of the curved surfaces of the lower ends 85 of the pawls, preventing further movement 15 of the totalizer pinions.

To prevent overthrow of the totalizer pinions, pawls 76 are carried into engagement with the pinions by action of nose 84 at the 20 precise moment that differential segments 52 come to rest in their moved positions. This effectually prevents overthrow amounting to more than a mere fraction of a unit of movement of the pinions, measured by 25 whatever backlash exists between nose 84 and the totalizer. To prevent tripping of the carrying devices by such possible slight overthrow, the carrying devices interlock with the totalizer at the lugs 96 and notches 97 so that as pawls 76 force the totalizer pinions to correct positions, the carrying devices are compelled to return to untripped 30 positions.

To permit resetting the totalizer, means 35 are provided for rocking the locking pawls 76 out of engagement with the totalizer pinions and for reversely rotating the pinions to zero positions. To this end each cam disk 91 of the totalizer is provided with a lug 107 (Fig. 11) extending into an annular groove 108 in the totalizer shaft. The totalizer shaft is also provided with a longitudinal groove 109 into which fits a plate 110 having cut-away parts 111 normally opposite the annular grooves 108; thus the plate normally does not prevent rotation of the totalizer elements as the lugs 107 have a clear passage through the grooves 108.

By shifting plate 110 so that its notches 50 111 are moved out of register with grooves 108 and then rotating the totalizer shaft 61 once, the plates 110 will engage lugs 107 in whatever positions these lugs may be, rotating them backwardly until their respective totalizer pinions reach their zero positions.

To effect rotation of shaft 61 it is provided with a semicircular shoulder 140 with its flat horizontal face fitting against a similar shoulder 141 on a sleeve 117 55 rounding a short shaft 242 fixed in the machine side frame 116. Fast to sleeve 117 is a knurled head 112 carrying a pin 113 extending into a notch in an annular groove 114 in a disk 115 fast to the frame 116, and 60 thus the knurled head 112 must be moved to

the left (Fig. 12) to carry pin 113 out of the notch before it may be rotated.

The sleeve 117 is provided with grooves 118 into which fit lateral extensions 119 of plate 110. By this means the plate is shifted when the knurled head 112 is shifted to the left to disengage it from disk 115. A spring pressed collar 143 loosely mounted on shaft 74 normally holds the knurled head in the position shown in the drawings preventing accidental displacement of the resetting mechanism and on one side forms a sharp edge engaging with the serrations on head 112, thus preventing its backward rotation. The sleeve 117 which carries the knurled head also carries a cam 121 engaging a plate 122 (Fig. 10) riveted to frame 78 and by means of this cam frame 78 is rocked to the right (Fig. 6) when the knurled head is rotated to rotate the totalizer, thus disengaging the locking pawls 76 from the totalizer pinions and permitting their rotation, and also causing nose 83 of the bell crank lever 80 to enter a notch 123 in disk 82, thus locking the machine against 90 operation during the resetting operation.

At resetting operations the totalizer pinions are prevented from rotating past their zero positions by lugs 96 contacting with teeth on disks 89, which, in turn, are prevented from rotating by engagement of the teeth 95 of disks 88 with the peripheries of cams 92. In the case of the pinion of highest order the locking disk 88 is engaged directly by a lug 144 (Fig. 8) on a disk 145 fast to the totalizer pinion, and disk 88 bears against the periphery of a disk 146 fast to the shaft 63. If the highest order pinion is given a more than nine units of movement by transfer operations before the totalizer is reset, a notch 147 in disk 146 permits rotation of disk 145 when engaged by lug 144, as when carrying is performed notch 147 is in position to permit rotation of disk 145.

Detail printing mechanism.—The amount type carriers 47 (Fig. 4) of the detail printing mechanism are secured to sleeves 124 which also carry pinions 125. (Fig. 1) constantly in mesh with the segments 52, thus 115 the differential movements of these segments are communicated to the type carriers 47.

The portions 38 of the initial key parts 24 carry pins 39 for entering slots 40 in arms 120 41 pivoted on a shaft 42. The arms 41 are rigid with a segment gear 43 meshing with a pinion 44 fast to a type wheel supporting shaft 45. The initial type wheel of the detail printing mechanism (Fig. 4) is fast to this shaft and is accordingly properly set by its differential rotation under the control of parts 24 of the initial keys.

An oscillating frame 132 is pivoted to the machine frame by a pin 133, and to oscil- 130

late this frame an arm 134 fast to the key coupler trunnion 9 is provided, having a pin 135 passing into a slot 136 in the frame 132. Mandrels 130 and 131 are mounted on this frame, and support respectively a paper supply roller 127 and a receiving roller 129. A curved writing table 128 is also carried by the frame 132 and the detail record paper 126 is wound from the supply roller 127 over the table or platform 128 and around the receiving roller 129. Frame 132 is oscillated at each movement of the coupler in order conveniently to permit autographic and printed records to be made side by side.

The receiving roller is fitted with a ratchet wheel 137 which is engaged and rotated to feed the paper by a pawl 138 when frame 132 is rocked rearwardly. Pawl 138 is pivoted to an arm 139 pivoted on a fixed pin 440 and having a handle 441 extending through an irregular slot 142 in a fixed plate 443 in which it may be adjusted to regulate the feed of paper 126. Arm 139 is provided with a slot 144 for receiving pivot pin 140 so that it may be adjusted to one side or the other of a shoulder 145 on plate 443. The slot 142 extends forward of shoulder 145 for some distance to permit manual operation of pawl 138 to feed the paper 126 independently of the driving mechanism of the cash register.

The platen 146 is spring actuated, the spring 147 being compressed by a cam 148 on drive shaft 21. A pawl 149 feeds an inking ribbon 150 by engaging a ratchet wheel 151 fast to an inking ribbon feeding roller 152. The pawl is reciprocated by being engaged at each operation by a lug 153 on frame 132.

Autographic attachment.—The autographic attachment shown in Fig. 4^a, is for the purpose of receiving more extended records of special transactions, for instance, dates and terms of sales, quality, grade, or time of delivery, etc., of articles sold. The autographic mechanism operates to feed a paper record a uniform distance at each operation of the machine, and it may be manually operated at will to feed the paper forward or backward.

The autographic mechanism comprises a suitable frame 154, in which are fixed two mandrels 155 and 156, one of which supports a spool for carrying the record paper and the other a spool for receiving the record paper as it is unwound. Milled disks 157 and 158 are fast to the spools and serve to rotate the spools backward or forward as desired. At the sides of the milled disks are retaining pawls 159 and 160 pivoted to the frame 154. Each pawl is provided with a curved tail 161 extending along the side of one of the milled disks as shown in the drawing. If an operator presses his finger

against one of the disks in order to rotate it, he will thereby, by pressing down on the tail 161 of the corresponding pawl rock it out of engagement with the other milled disk and, as the disk which he rotates is engaged by the remaining pawl, it is possible to rotate it only in the direction by which the paper is wound on the respective spool. Therefore if the paper is to be fed forward around the receiving spool, disk 158 is operated and if it is to be fed backward, disk 157 is operated. The pawls serve to prevent the record paper from sagging between the spools, because the moment the operator releases one of the disks, the pawl for the remaining disk is permitted to rock into engagement, thus both pawls are in engagement and prevent movement of the record paper.

The driving mechanism of the cash register has connections for operating the autographic paper feeding device in one direction, consisting of a pawl 162, pivoted on the mandrel 131 in the rocking frame 132 (Fig. 4) and having a limited rocking movement on its pivot. The pawl 162 is formed with an enlarged forward end 162^a which in its normal position lies above both the disk 158 and the tail 161 of the pawl 160. When frame 132 rocks rearwardly, a beveled lug 163 on the pawl engages a fixed lug 164 and the forward enlarged end 162^a of the pawl 162 is thereby forced into engagement with disk 158 and the tail of pawl 160, rotating disk 158 and holding pawl 160 out of engagement with its milled disk. On the return of frame 132, the lug 164 serves to hold pawl 158 out of engagement with the milled edge of disk 158.

Total printing mechanism.—The total printing mechanism is shown in Figs. 16 to 20. The mechanism is intended to be normally inaccessible as it is located beneath the cabinet lid, not shown in the drawings, but usual in this type of machine. The total printing mechanism is constructed to issue slips containing the printed total and also to retain a record of each printed total on a record strip fed from one roller to another, and thus retained in the machine. Both strips of record paper, the one from which the printed slips are detached and the one which serves to retain total records in the machine, are made to pass over a writing platform, one above and one below a piece of carbon paper or ink ribbon. This is to permit the one who operates the total printing mechanism conveniently to attest both records by signature. The principal object of the total printing mechanism is to facilitate auditing a number of machines in a single business or in a number of stores under one management.

Referring to the drawings: Fig. 16, a front elevation, shows the type wheels 60 of

the totalizer mechanism located beneath paper strips 165 and 166. These strips pass from supply rolls 167 and 168, around a guide roller 169, beneath the type wheels 5 and a platen 170 (Fig. 18), then between an electrotype roller 171 and an impression roller 172, and finally over a writing platform 173, provided with an inking ribbon in a holder 210. The strip 166 continues 10 from the writing platform around a roller 174 to a receiving roller 175.

Platen 170 is secured to an arm 176 fast on a shaft 177 and arm 176 carries a pawl 178 urged by a spring 179 so that its rearwardly extending tail rests on shaft 177 and its forward nose engages a shoulder 180 on a platen operating lever 181. A spring 182 urges lever 181 to assume the normal position shown in Fig. 20. To operate the 20 platen, lever 181 is rocked downward as far as permitted by its notch 183 co-acting with a fixed pin 184. At this movement shoulder 180 engages pawl 178, rocking the platen arm upward until shoulder 180 passes the 25 nose of pawl 178, when the platen arm 176 rocks downward under action of a spring 185 (Fig. 18), effecting an impression of the total on the two strips of paper. On the release of arm 181 the platen is raised 30 slightly from the paper by a spiral edge 201 engaging a pin 202 on the platen arm. An endless ink ribbon 186 passes between the two strips of paper and over the upper strip, around suitable guide rollers as shown in 35 Fig. 20. A drying roller 187 is provided with a knurled knob 188 by which the ink ribbon may be fed as desired.

After an impression is taken, the two strips of paper are fed forward by a crank 40 189 eccentrically pivoted on the electrotype roller 171 and having an arm 190 engaging a pin 191 on the electrotype roller. If the operator attempts by mistake to rotate the electrotype roller backwardly, he will 45 quickly be apprised of his mistake by the lack of resistance to rotation of the crank. The electrotype roller 171 is geared to a companion feed roller 172 and to the receiving roller 175 for the record strip 166, 50 by the gears 192, 193, 194, and 195, as shown in Fig. 16. As indicated in Fig. 18 the receiving roller 175 has a frictional connection with gear 195, caused by a spring 1751. As the diameter of the paper on roller 175 increases it tends to feed faster and would 55 soon break the strip except for this frictional connection.

Means is provided for preventing operation of the paper feeding mechanism before 60 the platen is operated, and while the platen is in its lower position resting on the record paper. This means also serves to limit the feed of the paper strips, and consists of pawls 196 and 197 pivoted on shaft 177 and 65 serving to obstruct a lug 198 on a disk 199

fast to a shaft 200, on which the electrotype roller 171 is rigidly mounted.

Neither of the pawls 196 or 197 is fast to shaft 177 but they are respectively urged by springs 203 and 204 to rock toward disk 70 199 and normally assume the positions shown in Fig. 19. Pawl 196 is normally held out of the path of the lug 198 by a pin 305 in shaft 177 engaging a segmental hub 3051 of the pawl. When the platen operating lever 75 181 is rocked downward, the platen is first forced upward, causing shaft 177 to rock pawl 196 so that a lug 205 at its lower end engages the tail 206 of pawl 197, rocking this pawl out of the path of lug 198, it being 80 understood that there is sufficient back lash in the pinions 194, 193 and 192 to permit of a slight retrograde movement of the disk 199 to permit of the disengagement of the pawl 197 from the lug 198. Pawl 85 197 is provided with a slot 207 surrounding shaft 177, which permits spring 204 to force it upward at the rear of the lug so that it will not reengage the lug when the platen is released. On the release of the 90 platen, when shoulder 180 (Fig. 20) passes out of engagement with pawl 178, the forward rocking shaft 177, carries pawl 196 below lug 198, preventing operation of the paper feeding mechanism while the platen 95 is in engagement with the type wheels and until lever 181 is permitted to return to normal position, when the platen and shaft 177 are restored to normal position by action of shoulder 201 on pin 202 on the platen 100 arm.

It is thought that the operation of the device is sufficiently set out in detail in the foregoing description as not to require a separate detailed description here. Briefly 105 stated, to make an entry in the machine, the operator first slightly depresses an initial key 2 (Fig. 2), thus lifting its rear end 24 far enough to make the supporting device 25 effective. Then, by operation of one or more 110 value keys, the key coupler is lifted and the rear part 24 of the depressed initial key, together with the operated value keys, are lifted into engagement with their respective indicator rods 5, thereby setting the indicators. The key coupler engages the foot of upright 28 which supports the screen 27, moving the screen to concealing position, but the screen immediately lowers with the key 115 coupler as its supporting latch 30 is held out of supporting position by the lug 35 on the upright for the initial indicator. If the machine is operated by the depression of value keys alone, screen 27 will remain in concealing position, thus making evident an 120 irregular operation of the machine.

The oscillation of the key coupler effects rotation of the main shaft 21 (Fig. 1) through the rack 15. The first work accomplished by shaft 21 is to rock the totalizer 130

into mesh with the actuating pinions 73 by cam 70 (Fig. 10). The segments 52 (Fig. 1) are then differentially actuated by the uprights 55 on the keys engaging the differently set bell crank levers 50 fast to the segments. Differential movements of the segments are communicated to the totalizer through the pinions 75 and 73. After this is accomplished and while the segments 52 are at rest, cam 71 (Fig. 10) returns the totalizer out of mesh with the pinions 73 and the carrying mechanism becomes effective, as mutilated pinion 101 (Fig. 6) engages pinion 104, through it rotating shaft 63 on which are fact the operating disks 92 for the carrying mechanism.

The type carriers of the printing mechanism (Fig. 4) are set by segments 52 meshing with pinions 125 (Fig. 1) fast to sleeves rigid with the type carriers, and by segment 43 (Fig. 2) controlled by the initial keys.

The autographic frame 132 (Fig. 4) is rocked rearwardly while the type carriers are being set, by its connection 134 with the key coupler. During this movement the record paper 126 is fed as ratchet 137 passes pawl 138 and thus if an autographic notation is made on the record strip previous to the operation of the machine, it is brought to the side of the type wheels to be substantially in a line with the printed record which is made when frame 132 is in its rear position. The rearward movement of frame 132 also effects feeding of the paper of the autographic attachment shown in Fig. 4^a, through pawl 162.

If at any time it is desired to ascertain the total amount which has been accumulated by the totalizer, or to obtain a printed statement of the amount for auditing, the cabinet lid is unlocked and handles 181 and 189 (Fig. 18) are operated in succession. The first effects printing of the total by operation of platen 170 and the second, operation of electrotype roller 171, thereby feeding the strips 165 and 166 and printing on the upper strip a consecutive number, and character and rulings to identify the machine and indicate places for receiving autographic records of the date, and the name of the operator, the paper coming into proper position for such purpose over the writing platform 173. Written records on the upper strip are transferred to the lower strip by the inking ribbon in holder 210.

If it is desired to reset the totalizer to zero after a total printing, this may be done by rotating milled head 112 (Figs. 11 and 12), thus causing plate 110 to shift to operative position and rotate the totalizer pinions backwardly to zero. The carrying mechanism is not tripped on resetting operations as the totalizer pinions do not pass the zero position.

While the form of mechanism herein

shown and described is admirably adapted to fulfil the objects primarily stated, it is to be understood that it is not intended to confine the invention to the one form of embodiment herein shown and described, as it is susceptible of embodiment in various forms, all coming within the scope of the claims which follow.

What is claimed is:

1. In a machine of the class described, the combination with a totalizer, of a pivoted actuating segment therefor, a plurality of bell crank levers helically arranged with respect to the pivot of the segment and rigid with the segment, a corresponding reciprocating member for each bell crank lever, and means for moving any one of said members to engage one arm of its corresponding bell crank lever and thereby rocking the segment, said reciprocating member positioned to be engaged by the other arm of the bell crank lever to prevent overthrow of the segment.

2. In a machine of the class described, the combination with a group of keys, and reciprocating members carried by said keys and all identical in size, of a totalizer, an actuating device for said totalizer, and helically positioned arms fast on said actuating device, and each constructed to be engaged by the corresponding reciprocating member.

3. In a machine of the class described, the combination with a group of keys, and standards carried by said keys, identical in size, and each having on operating edge, of a totalizer, an actuating device for said totalizer, and helically positioned lever arms fast to said actuating device, and constructed to be engaged by the corresponding key standard.

4. In a machine of the class described, the combination with a group of keys, and vertical standards carried by said keys, all identical in size and having hooks at their upper ends, of a totalizer, an actuating device for said totalizer, a rod normally engaged by said standard hooks and against which said standards ride when said keys are operated, and helically positioned bell crank levers all fast to said actuating device, and each having both an arm against which the corresponding standard engages, and an arm positioned to strike the said corresponding standard before the end of the key stroke.

5. In a machine of the class described, the combination with a group of keys, and standards carried by said keys, all identical in size and each having an operating edge, of a totalizer, an actuating device for said totalizer, helically positioned arms all fast to said actuating device, and against which operating edges of said standards first engage and then slide past, a type carrier, connections from said actuating device to drive

5 said type carrier, means for taking impressions from said type carrier, and connections, driven by said keys, for actuating said impression means as said operating edges of said standards slide past said positioned arms.

6. In a machine of the class described, the combination with a totalizing device including type carriers, of means for differentially setting the totalizing device, an impression device co-operating with the type carriers, means for operating the impression device, a paper feeding device, means for operating the paper feeding device, and an interlock 10 between the impression device and the paper feeding device requiring an operation of the impression device before the paper feeding means may be operated.

7. In a machine of the class described, the combination with type carriers of means for differentially setting the same, a platen, paper feeding mechanism, separate means for operating the platen and the paper feeding mechanism, and an interlock 20 between the platen and the paper feeding means preventing an operation of the latter when the platen is in operation.

8. In a machine of the class described, the combination with a totalizing device, of a 25 differential mechanism, mechanism for engaging and disengaging the totalizing device and the differential mechanism, an alining and locking device for the totalizing device, means for making the alining and locking devices effective when the totalizing device is out of mesh and while the totalizing device is in mesh and the differential mechanism is at rest.

9. In a machine of the class described, the 30 combination with an accounting device, of an operating mechanism, and keys for controlling the accounting device, including a depressible key having two parts having a like and joint movement when depressed and one of which is constructed to become connected to the operating mechanism and is movable therewith independently of the other part of the key.

10. In a machine of the class described, the combination with an accounting device, of an operating mechanism, and keys for controlling the operation of the accounting device, including a key having two parts having a like and joint movement when depressed but one end of which is free to return to normal position while the other is constructed to require an operation of the operating mechanism before it may return to normal position.

11. In a machine of the class described, the combination with a plurality of banks of keys, of indicators the setting of which is controlled by the keys, an indicator screen, connections whereby the depression 65 of keys causes the screen to move to conceal-

ing position, means for latching the screen in concealing position, and means under the control of but one bank of keys for disabling said latch.

12. In a machine of the class described, 70 the combination with a plurality of keys, of indicators the setting of which is controlled by the keys, an indicator screen, connections whereby the depression of keys causes the screen to move to concealing position, means for latching the screen in concealing position, and connections whereby a limited number of keys may disable the latch.

13. In a machine of the class described, 80 the combination with a plurality of banks of keys, of indicators the setting of which is controlled by the keys, an indicator screen, connections whereby the depression of keys causes the screen to move to concealing position, a spring operated latch for retaining the screen in concealing position, and a device operated by one of the keys for making the latch ineffective.

14. In an accounting machine, the combination with a plurality of type carriers, of 85 depressible keys for differentially setting the type carriers, a key coupler, a paper carrying frame, and connections whereby said frame may be shifted by the key coupler alternately between a position in which it 90 may receive autographic records and the printing position.

15. In an accounting machine, the combination with printing mechanism, of an 100 oscillatory paper carriage, a ratchet wheel journaled in the carriage for feeding the paper, a pawl positioned to engage the ratchet when the carriage is oscillated, and an adjustable device on which the pawl is 105 pivoted.

16. In a machine of the class described, the combination with two rotatable paper carrying spools, of ratchet disks, one fixed to each spool, and pawls engaging the 110 ratchet disks, and having tails extending substantially parallel to and normally slightly above the ratchet teeth of the disks, whereby an operator may depress one of the pawl tails by a movement to actuate the 115 adjacent ratchet disk.

17. In a machine of the class described, the combination with two rotatable paper carrying spools, of ratchet disks, one fixed to each spool, and pawls, each engaging the 120 teeth of one of said ratchet disks and having a tail extending substantially parallel to and normally slightly above the ratchet teeth of the other of said disks, whereby an operator may release the pawl from one ratchet disk 125 by a movement to actuate the other ratchet disk.

18. In a machine of the class described, the combination with a group of keys, and standards carried by said keys and all iden- 130

tical in size; of a totalizer; an actuating device for said totalizer constructed to be engaged by the key standards; and a zero stop for normally preventing displacement of said actuating device and constructed to be engaged by the standard of any key to render it ineffective for such purposes upon operation of the key.

19. In a machine of the class described, 10 the combination with type carriers; of means for differentially setting the same; a platen; paper feeding mechanism; means for operating the platen and the paper feeding mechanism; and an inter-lock between the platen 15 and the paper feeding means preventing an operation of the latter when the platen is in operation and also preventing the operation of the platen until after the paper feeding device has been operated.

20. In a machine of the class described, 20 the combination with a totalizer; of a differential mechanism; mechanism for engaging and disengaging the totalizer and the differential mechanism; an alining and 25 locking lever for said totalizer; a carrying frame for said lever; a cam for rocking said frame to make said lever effective while the totalizer is in mesh with the differential mechanism and the differential mechanism 30 is at rest; and an additional cam for engaging said lever to retain said lever in effective position when the totalizer is out of mesh with the differential mechanism.

21. In a machine of the class described, 35 the combination with totalizer pinions; of a cam; alining pawls operated by said cam to reposition said pinions if they are overthrown a fraction of unit of movement; and carrying devices constructed to be set when 40 a totalizer pinion passes from the "nine"

position to "zero" position and including a member fast to said cam and arranged to interlock with the totalizer pinions and thus to be restored by the alining pawls if moved by an overthrow of said totalizer pinions. 45

22. In a machine of the class described, the combination with a plurality of type carriers; of a paper carrying frame normally in a position in which it may receive autographic records; and depressible keys 50 for differentially setting the type carriers and shifting said frame into printing position.

23. In a machine of the class described, the combination with an accounting device; 55 of an operating mechanism; and keys for controlling the accounting device, including a depressible key having two pivoted parts, jointly movable when depressed and one of which is constructed to become connected to 60 the operating mechanism and is movable therewith independently of the other part of the key.

24. In a machine of the class described, the combination with an accounting device; 65 of an operating mechanism; and keys for controlling the operation of the accounting device; including a key having two pivoted parts jointly movable when depressed but one part of which is free to return to normal position while the other is constructed to require an operation of the operating mechanism before it may return to normal 70 position.

In testimony whereof I affix my signature 75 in the presence of two witnesses.

JOHN A. WERNER.

Corrections in Letters Patent No. 1,125,613.

It is hereby certified that in Letters Patent No. 1,125,613, granted January 19, 1915, upon the application of John A. Werner, of Dayton, Ohio, for an improvement in "Total-Printing Cash-Registers," errors appear in the printed specification requiring correction as follows: Page 8, line 99, for the word "standard" read *reciprocating members*; same page, line 103, for the word "to" read *on*; and lines 104-105 for the words "key standard" read *reciprocating member*; and that the said Letters Patent should be read with these corrections therein that the same may conform to the record of the case in the Patent Office.

Signed and sealed this 16th day of March, A. D., 1915.

[SEAL.]

J. T. NEWTON,
Acting Commissioner of Patents.
